ABSTRACT

A self contained electromagnetically resonant device includes a resonant circuit assembly encapsulated in an elastomeric material surrounded by a rigid casing. The resonant circuit includes an elongated core of sintered magnetically soft material and a coil connected across a capacitor which is spaced from the core. The elastomeric filler co-acts with the casing to substantially retain the core in its original form and dimension in the event of core breakage to maintain the resonant frequency and quality of the resonant circuit assembly. The device is resonantly excited solely by exposure to an electromagnetic or magnetic field having a suitable frequency component.

5 Claims, 6 Drawing Figures

ELECTROMAGNETICALLY RESONANT DEVICE

The present invention relates to electromagnetically resonant devices, particularly devices having a relatively fragile magnetic core material which is suitably protected to maintain satisfactory resonance operation even in the event of core breakage.

A self-contained passive resonant circuit is disclosed in co-pending application Ser. No. 325518 filed in the name of D. Zimmermann et al. on Jan. 22, 1973 now U.S. Pat. No. 3836842. The resonant circuit includes a ferrite core and an inductor connected across a capacitor. The circuit is intended for use in a field environment which dictates that it must withstand rough handling without significant degradation or change in its resonant frequency or quality. It was found that rough handling tended to break or shatter the core material, a sintered magnetically soft material often referred to as a ferrite. Such breakage usually alters the resonant frequency and quality, to such an extent, that the device becomes unusable for the purpose intended, i.e. as an electromagnetic marker. It was determined that less fragile cores, for example of sheet laminates or rod bundles, did not have magnetic properties best suited to device operation.

Hence in the above mentioned application, a resonant circuit assembly encapsulated in a material at least as brittle as the ferrite core material is disclosed. This carries the advantage that if the core became fractured the encapsulation is likewise fractured and an unserviceable device is so identified by visual inspection. This at least prevents unserviceable devices from being installed or buried as markers which would not, in some cases, resonate adequately to be located.

This form of encapsulated resonant circuit has various minor disadvantages. Although it is reinforced by the encapsulation, a substantial fraction of the total are damaged before use. Core breakage in the area of the coil winding may not be detected visually because of the reinforcing effect of the wire in the induction coil. In some cases, this reinforcing initially permits only a hair line type of fracture, easily overlooked during a visual inspection.

The present invention provides an encapsulation which, in the event of core breakage or shatter, resiliently maintains the core form and dimension. Consequently, resonant frequency and quality of a device is substantially maintained. As long as the other shell of the device remains unbroken, that device will function satisfactorily in the field, as a marker, regardless of the mechanical integrity of the core.

Difficulties have been encountered, in mass producing a coil wound upon an elongated core, as described in the above mentioned co-pending application. The ferrite core material is fragile and not economically formable into very straight lengths. Hence typical coil winding machines tend to shatter the matter if winding directly on the core is attempted. If an elongated bobbin is used to carry the desirably elongated coil, the bobbin must be flexible enough to accommodate deviations in the ferrite core. Again, bobbins of preferred flexibility are not readily adaptable to typical mass production coil winding methods.

Some difficulty was experienced in producing resonant devices having a suitable high resonant quality. It was found that the capacitive element of the resonant circuit if placed next to the core, significantly reduced

the potential quality of resonance of the circuit. To avoid this, the capacitor is spaced apart from the core.

The present invention is a self contained electromagnetically resonant device, excitable solely by exposure to an electromagnetic or magnetic field having a suitable frequency component. The device comprises a resonant circuit assembly including a coil residing on an elongated core of sintered magnetic material and a capacitor connected across the coil and spaced adjacent the core. The resonant circuit assembly resides within a rigid hollow casing and is surrounded by an elastomeric filler contiguous with the assembly and with the walls of the casing. In the event of core breakage, the elastomeric filler co-acts with the casing to substantially retain the core in its original form and dimension, so that the resonant frequency and quality are substantially maintained.

The present invention also includes a relatively short coil carried on a bobbin having an interior dimension substantially greater than the thickness of the core and resilient gripping means to maintain the required position of the coil relative to the core. The bobbin is robust to be compatible with typical mass production coil winding methods.

25 The present invention also includes a retaining member which carries the resonant circuit assembly of the core and the coil spaced apart sufficiently from a capacitor, to prevent any substantial reduction of the quality of resonance of the circuit.

30 An example embodiment of an electromagnetically resonant circuit device is discussed in the following with reference to the accompanying drawings in which:-

35 FIG. 1 is a side elevation of an electromagnetically resonant device in accordance with the invention;

FIG. 2 is a cross-sectional view taken along a line II-II in FIG. 1;

FIG. 3 is an exploded assembly view of the device in FIG. 1;

40 FIG. 4 is a side elevation of one part of the device in FIGS. 1 and 2;

FIG. 5 is a top view of the part in FIG. 3; and

FIG. 6 is a cross-sectional view taken along a line VI-VI in FIG. 3.

45 Referring to the drawings a resonant circuit assembly includes an induction coil 4 and a ferrite core 5 wound on a bobbin 32. The bobbin 32 includes a pair of resilient fingers 33 extending from one end thereof. The bobbin 32 is coaxially carried on the core 5. The core 5 includes six longitudinal channels 6 formed therein. The channels 6 provide a much larger surface area on the core 5 than if the core were of a plain circular cross-section. The coil 4 is connected via leads 7 across a capacitor 8. The core 5, the coil 4 and the capacitor 8 constitute an electrically resonant circuit assembly which resides within a rigid outer casing 10. The remaining volume in the casing 10 is occupied by an elastomeric material 35 and a retaining member 20.

55 The retaining member 20 includes a hollow projection 21 which engages the inner surface of the wall of the casing 10. One end of the projection 21 terminates at an outwardly projecting grooved shoulder 23. The other end of the projection 21 terminates at an end wall 35 which carries a hollow cylindrical projection 25, within which an end of the core 5 resides. The interior of the hollow projection includes a pair of resilient retaining fingers 29, extending on one side thereof from

60

the end wall 25 and another resilient retaining finger 28 opposite the fingers 29 and likewise extending from the end wall 25. The end portions of the retaining fingers 28 and 29 are adapted to grasp and retain the capacitor 8, which is of tubular form. The hollow projection 21 includes a pair of captive openings 22 to facilitate the placement of the capacitor 8 and connection of the coil 4 thereto.

The casing 10 includes a large diameter portion 11, terminating at shoulders 16 and 17 which extend into lesser diameter portions 12 and 13 respectively. As illustrated in FIG. 3, the end of the lesser diameter portion 13 tapers away from the large diameter portion 11 and terminates at a blunt end 15. The walls of the casing 10 include a plurality of longitudinal reinforcing formations 14 to enhance the longitudinal rigidity of the casing 10.

In assembly of the device the electrical components are held by the retaining member 20. The electrical components of the assembly are of course of such value that the circuit will resonate within a narrow predetermined frequency range. The exact resonant frequency desired is obtained by exciting the circuit to resonance and adjusting the position of the coil 4 along the length of the core 5 to obtain the exact desired frequency of resonance. The fingers 33 provide gripping means to hold the coil 4 carried by the bobbin 32 at the desired position on the core 5 during the remainder of the assembly operation. The casing 10 is filled to a certain level with a curable liquid resin material. The electrical components and the retaining member 20, as one unit, are inserted into the casing until the shoulder 23 fits against the end of the portion 12. The interior of the bobbin 32 is of sufficient diameter to permit a layer of the resin to flow between the core 5 and the bobbin 32. The assembled device can be viewed looking into the hollow projection 21 which should now be substantially filled, as is the remainder of the casing 10, with the resin material. After the resin is cured the device is ready for use.

The resin in its cured state provides the elastomeric material 35. The elastomeric material 35 is by nature substantially incompressible. In other words the volume of the filler 35 remains substantially constant even under considerable stress. As before mentioned the elastomeric material 35 is contiguous with the casing 10 and the items contained within. The channels 6 provide a relatively large surface area on the core 5 which enhances the retaining action of the encapsulation upon the core 5. The large diameter portion 11 of the casing 10 provides space for an adequate amount of the elastomeric material between the coil and the wall of the casing 10. The shoulder 16 restrains the material 35 from any tendency to work its way through the portion 12 and out of the end of the casing 10.

With the core length between about 6 and 8 inches in length, it has been found that the capacitor must be separated from the end of the core by at least one-fourth of an inch. This minimizes the velocity and density of magnetic flux cutting through the plates of the capacitor sufficiently to avoid a significant reduction in the quality of the resonant circuit.

In one embodiment the casing 10, and the retaining member 20 are of a high density polyethylene material. The casing 10 is formed by blow molding in a well known manner. The assembly fixture 20 is also of a high density polyethylene material however somewhat

rigid than the material of the casing 10 so that the retaining fingers 28 and 29 have adequate resilience to facilitate the placement and retention of the capacitor 8. The fingers 28 and 29 may be substituted by a raised projection or pedestal upon which the capacitor rests. However this may require some other means for holding the capacitor in position at least until the material 35 has cured. The bobbin 32 is of a stabilized polypropylene material. The elastomeric material 35 is a polyurethane compound of the non-adhesive type. For example, a polyurethane material supplied by Baker Castor Oil Co. in Bayonne, N.J., U.S.A. in curable resin form, under the trade name of System 86 or System 27 Polyurethane, has been found suitable.

In the event of a severe momentary mechanical shock or stress to the device, it is likely that the ferrite core material will break while the casing 10 will typically only flex. Any tendency for dimensional change of the core 5 is substantially resisted and prevented by the polyurethane material 35 retained in the casing 10. Resonant frequency shifts of typically less than about 4 percent have been experienced, in devices initially resonant at about 65 KHz and in which a majority portion of the core has become shattered. These damaged devices remain effectively useful as electromagnetically resonant marking devices.

What is claimed is:

1. A self contained electromagnetically resonant device, excitable solely by exposure to an electromagnetic or magnetic field having a suitable frequency component, the device comprising:

a rigid hollow casing;

a resonant circuit assembly having, an elongated core of sintered magnetically soft material, a coil of conductive material encircling a portion of the core, and a capacitor connected across the coil, the capacitor being spaced from the core to reduce magnetic flux velocity through the plates of the capacitor, the assembly residing within the casing, spaced adjacent the wall thereof;

an elastomeric filler within the casing, surrounding said assembly, contiguous therewith and with the walls of the casing, the elastomeric filler co-acting with the casing to substantially retain the core in its original form and dimension, in the event of core breakage, so that the resonant frequency and quality of the resonant circuit assembly is substantially maintained.

2. A device as defined in claim 1 in which the core includes a plurality of longitudinal channels, said channels providing a relatively large surface area contiguous with said elastomeric filler to enhance said retaining action.

3. A device as defined in claim 1 in which the coil resides on a bobbin carried by the core, the interior of the bobbin being of greater dimension than the thickness of the core and a layer of the elastomeric filler residing between the core and the interior surface of the bobbin, the bobbin including resilient gripping means for maintaining the coil at a desired position along the core prior to and during final assembly of the device.

4. A device as defined in claim 1 in which the hollow casing open at one end and includes a retaining member for holding the elements of the resonant circuit assembly in position during assembly of the device, the retaining member comprising:

a wall defining an interior cavity and mating with the inner surface of the casing adjacent the opening; a shoulder terminating one end of the wall and in abutment with the end of the casing wall; a retaining cup terminating the other end of the wall, 5 one end of the elongated core residing within the retaining cup; spacer means protruding into the interior cavity and carrying the capacitor spaced adjacent the one end of the core; 10 the wall of the retaining member including a captive opening adjacent the spacer means, the opening providing for placement of the capacitor adjacent the spacer means and for the flow of the elastomeric material in its uncured state during insertion 15 of the resonant circuit assembly into the casing.

5. A self contained electromagnetically resonant device, excitable solely by exposure to an electromagnetic or magnetic field having a suitable frequency component, the device comprising: 20

an elongated rigid hollow casing, open at one end and including a plurality of longitudinal reinforcing formations in the wall of the casing, the end portion of the casing adjacent the open end thereof being of lesser cross-sectional area than the middle portion of the casing, the middle and end portion being 25

joined by a shoulder portion of the casing wall; a resonant circuit assembly having, an elongated core of sintered magnetically soft material, a capacitor, and a bobbin carrying an inductor and residing on the core, the inductor electrically connected across the capacitor, the bobbin including a pair of spring fingers extending from one end of the bobbin to frictionally grip the core, to retain the inductor thereon;

a retaining member carrying the resonant circuit assembly and fitting into the open end of the casing to maintain the resonant circuit assembly within and spaced from the wall of the casing and to maintain the capacitor spaced adjacent the end of the core during assembly of the device;

an elastomeric filler, surrounding said assembly, contiguous therewith and with the walls of the casing, and constrictively retained within the casing by said shoulder portion of the casing wall, in the event of a core breakage, the elastomeric filler co-acting with the casing to substantially retain the core in its original form and dimension, so that the resonant frequency and quality of the resonant circuit assembly is substantially maintained.
